REFLECTOR FOR AN INDUSTRIAL SAFETY LIGHT

Shinjiro Mori, Tokyo, Japan, assignor to Mori Denki
Manufacturing Co., Ltd., Tokyo, Japan, a company of
Japan

Filed Jan. 2, 1968, Ser. No. 10,000

Claims priority, application Japan Sept. 23, 1967

Term of patent 14 years

Int. Cl. D26—04, 99

U.S. Cl. D48—16

FIG. 1.

FIG. 2.

FIG. 3.

FIG. 4.

FIG. 5.

FIG. 6.

FIG. 1 is a top plan view of the reflector showing the new design;

FIG. 2 is a bottom plan view thereof;

FIG. 3 is a side elevation view thereof;

FIG. 4 is a sectional view thereof taken on line IV—IV of FIG. 1; and

FIG. 5 is a sectional view of the reflector mounted on an industrial safety light which is shown in broken lines for illustrative purposes only.

FIG. 6 is a perspective view of the reflector.

The characteristic feature of the reflector resides in the hollow opaque tubular members on the outer surface thereof having the ends cut off at the respective angles to the longitudinal axis of the tubular members as shown.

I claim:

The ornamental design for a reflector for an industrial safety light, as shown and described.
